METHOD OF MAKING THREE DIMENSIONAL IMAGES

Hans E. Holiman, Oxnard, Calif., assignor to
Beryl B. Hunt, Santa Barbara, Calif.

No Drawing. Application November 3, 1955
Serial No. 544,839

7 Claims. (Cl. 41—24)

My invention relates to the creation of individual images in bas-relief by a combination of photo engraving and repoussé.

The fabrication of three dimensional portraiture has long been sought without achieving any satisfactory results that were acceptable and at the same time economically feasible. For example, photographs of persons have been glued over malleable metal sheets and the sheets have been deformed by working or pressing from the reverse side. In this fashion the nose, chin, and forehead, etc. of the photograph have been projected forward, the eyes have been recessed and otherwise the portrait has been worked to give a bas-relief. Standard repoussé techniques have yielded even less realistic impressions.

None of the presently available methods are effective for forming small likenesses of persons similar in size and appearance to the impressions made on modern coins. There has been a demand for such small scale bas-relief for several decades as keepsakes, lockets, bracelet tokens and decorative jewelry and novelties. The cost of making a coining die, of course, is prohibitive for individual pieces, and the hand carving of pieces of metal to form the coin directly are equally prohibitive. Ordinary repoussé techniques have been unavailing as the fine detail required makes this work as demanding as hand carving of the solid metal piece.

I have discovered that photo etching can be combined with repoussé techniques for forming images on metal simulating the size and character of portraiture on modern coins. Furthermore, my invention lends itself to large scale production of individually different pieces. In addition my invention permits working of the pieces by relatively unskilled persons in a relatively short time. Such coin-like bas-reliefs accordingly may be produced at a cost of several dollars each as compared to a cost of several hundred dollars each for individually carved likenesses on metal.

It is therefore a general object of my invention to produce bas-relief images on metal with great fidelity and low cost.

Another object is to provide a photo etching and repoussé technique that results in small bas-relief images of great detail.

Still another object is to provide low relief images of persons on metal similar to a coin in size and in appearance.

A further object is to produce inexpensively and with clarity an image on metal wherein hand work may be performed by unskilled persons.

Other objects and features of my invention will be apparent in the following description and claims.

In carrying out my invention a photograph of the object to be reproduced in metal is first obtained. For most memento and jewelry purposes any ordinary photograph is suitable. A photograph may, however, be specially made for the particular person or object to be depicted in metal. If the photograph has sufficient con-

2

trast and shadow, it may be utilized directly for photo engraving. More commonly, however, it is desirable to convert the photograph to a black and white form devoid of shading or variations in contrast.

5 I prefer, at present to so prepare the photograph for etching that the background about the object will be etched away leaving the image projecting above this etched away metal. This provides a distinct physical outline for the entire image. In addition, the photograph is preferably so formed that lines distinguishing important parts of the image are etched. For example, on a portrait, the hair line, eyebrows, nose line, mouth and ear outline are ordinarily made on the black and white (or darkened and transparent) photograph, preferably on a transparent medium. This image is then projected or printed on metal or other material having a photo-sensitive coating as is well known in the photoengraving art. After the usual washing or other treatment, the sheet material is ready for etching and the etch removes metal at the lines photographically formed as well as removing the background.

This etched sheet is next pressed from the reverse side against a surface. This may be done manually by rubbing with a wooden pin or rod, but preferably is done 25 by a pressing, such as a rubber sheet placed on the back side and pressed in a press or machine delivering a uniform blow. This pressing causes the metal to be indented at the edge of the etching or engraving and in this fashion a true mirror image of the etched portions is obtained. This acts as a guide in perfect registry with the photoengraved image, thus simplifying the repoussé work to be done in pushing out the image portions from the reverse.

30 The worker may then push out the various parts of the image that must project to give proper bas-relief. For example on portraits, the forehead, nose, chin and cheekbones may be projected and the teeth, eyes and ear interior may be recessed. This pressing is well known in the repoussé art. While this work is ordinarily done 35 by hand, standard dies may be employed where the image size is the same for portraits of different persons and the view is the same, for example, full face view, profile or three quarter.

After the repoussé work is finished, the obverse side 40 may be worked by reverse repoussé, hand engraving tool, etc. to give the fine details to the image thus produced. It is a feature of my invention, however, that such metal working can be minimized or eliminated completely. By properly selecting the photograph or touching up photographs or black and white reproductions of photographs, the photoengraving will bring out these fine features so necessary to faithful and artistic reproductions.

45 Thus ordinary photographs can be so taken that the individual teeth will be photo etched, the wrinkles and dimples on skin will be reproduced, hair swirls and even individual hairs may be reproduced. This is particularly so when the photograph or touched up photograph is large in size. These fine details will then show up on the greatly reduced photoengraving of coin size.

50 Having once finished the bas-relief on thin metal sheet or other sheet material, the resemblance to a coin can be completed by molding to the metal sheet a solid such as plastic, plaster or solder, and the whole piece may be coated to give an appearance of uniformity of material. In this way three dimensional figures may be formed on thin copper sheet, the backing and sheet copper plated to a uniform color and surface that cannot be distinguished from a coin of uniform metal.

55 A modification of my invention is the printing on the reverse side of the sheet of a mirror image of the image to be formed on the obverse side. This printing is preferably done by a photomarking process. This photo-

marking may be a visible impression on a photosensitive covering on the metal or sheet or may be an actual photo etch or photoengraving. In any event the photomarking need be only very slight inasmuch as it serves as a guide only and not as permanent ornamentation. The repousse working merely uses this marking on the reverse side as a guide in pushing out the metal to form the bas-relief on the obverse side.

This reverse side marking is most effective however when it is employed with an obverse side photoengraving. The photoengraving outlines the image as well as the features and ornamentation thereof as previously discussed thus increasing the realism effect compared to a plain repousse. In such cases the reverse side image is a mirror image in registry with the image on the obverse side.

In actual production I have found that it is desirable to work on a photograph of relatively large size, for example, two inches square or larger. A number of photographs thus prepared may be then reduced in size optically until they are the desired "coin" size, for example, three quarters of an inch or less. Such reproductions may be placed upon a strip of film for example, a 35 mm. film, 16 mm. film, or other commercial type of film strip. This film may be adhered or otherwise closely placed against a copper strip of similar dimensions and the image printed upon the photosensitized copper strip. The individually etched images may be cut from the strip for individual working and the etched surface may be placed against a solid metal surface and pressed from the rear with a rubber sheet to create the indentations outlining the image and the features thereof. The worker may manually press out the image using these indented features as a guide, thus finishing the repousse work.

Various embellishments of the repousse work may be obtained, the most spectacular of which is the reproduction of a photograph image on top of the repousse. For this purpose the work may be done in silver metal or the metal itself silver plated and then photosensitized by forming appropriate silver salts or compounds thereon. The photograph image is then projected on the repousse work in registry therewith giving precise photographic details of all sorts.

Another type of embellishment is done by merely darkening the finished repousse and then rubbing off the high points to create highlights. In most types of work I prefer to finely sandblast the finished work so as to remove the smooth metal surface from the unetched portions thereof giving an increased artistic effect.

Various other modifications, variations and embellishments of my photoengraving process will be apparent to those skilled in the art. Accordingly, I claim all such modifications and variations as come within the true spirit and scope of my invention.

I claim:

1. The method of forming a three dimensional image on a sheet of deformable metal comprising; photoengraving one side of said sheet to outline the image thereon and to mark out important features thereof; pressing

the engraved side of said sheet against a surface by applying pressure to the reverse side until the reverse side of the sheet is indented at the engraved portions thereof and pressing the reverse side of said sheet locally within the outline and deforming portions marked by the feature engravings to form a bas-relief on the engraved side thereof.

2. The method of forming a three dimensional image as set forth in claim 1 wherein the bas-relief is worked on the obverse side to complete the details of three dimensional image.

3. The method of forming a three dimensional image in bas-relief on a sheet of deformable metal comprising: photoengraving a two dimensional representation of said image on the obverse side of said sheet to delineate important features thereof; coating the reverse side of said metal sheet with a photosensitive compound; optically projecting upon the reverse side of said sheet the mirror image of the engraved image and in registry with said engraved image so that the reverse side is photomarked on said photosensitive compound; and pressing said sheet on photomarked portions thereof to deform said sheet into a bas-relief on the obverse side thereof.

4. The method of forming a bas-relief image on a sheet of deformable metal comprising: coating the reverse side of the metal sheet with a photosensitive compound; optically projecting upon the reverse side of said sheet a mirror image of the bas-relief to be produced to photographically mark the reverse side with said mirror image; and pressing said reverse side locally within the photomarkings to deform the sheet and form a bas-relief on the obverse side thereof.

5. The method of forming a three dimensional image in bas-relief on a sheet of deformable metal comprising: photoengraving a two dimensional representation of said image on the obverse side of said sheet to delineate important features thereof; marking the reverse side of said sheet with the mirror image of said photoengraving and in registry with said photoengraving; and pressing said sheet from the reverse side within the confines of said mirror image to deform the sheet into a three dimensional image.

6. The method of claim 5 wherein the marking on the reverse side is obtained by pressing the sheet against a surface and indenting it locally in the lines of the photo etch.

7. The method of claim 5 wherein the marking on the reverse side is a photo marking accomplished by coating the reverse side with a photosensitive compound and thereafter optically projecting a mirror image of said bas relief image upon said reverse side.
